United States Patent Office.

DANIEL S. COLBY AND ROBERT SCORER, OF TROY, NEW YORK.

Design No. 3,050, dated May 26, 1868.

DESIGN FOR A COOK'S-STOVE PLATE.

The Schedule referred to in these Letters Patent and making part of the same.

TO ALL WHOM IT MAY CONCERN:

Be it known that we, DANIEL S. COLBY and ROBERT SCORER, of the city of Troy, in the county of Rensselaer, and State of New York, have invented or originated a new Design for Cooking-Stove Plates, of which the following is a full and exact description, reference being had to the accompanying drawing, and the letters of reference marked thereon, making part of this specification.

Our said design consists in or is composed of parts, as follows:

A is a side or jamb-plate of a cooking-stove, and it has a moulding, *m*, at its edges or borders.

B is the main oven-door of said plate, and has for its edge or surrounding moulding, a flat strip, *k*, with a series of diamond or lozenge-shaped projections arranged thereon, together with a sloped side and square bead or fillet at its bottom or edge of contact with said side-plate, all as shown in said drawing. Upon the central part of the panel of said oven-door is arranged the ornament *e*.

C is the extension-oven door, and it has the same pattern of surrounding moulding, *k*, as the oven-door B, and upon the central part of its panel is placed the ornament *g*.

D is the fire-door of said side-plate, and it has the same pattern of surrounding moulding as the oven-doors aforesaid, and has placed upon its panel the ornament *f*, as shown in annexed drawing.

What we claim as our invention or production, is—

The design for cooking-stove plates, as herein set forth and shown in annexed drawing.

DAN'L S. COLBY,
ROBERT SCORER.
